FRANK CANFIELD, OF DENVER, COLORADO, ASSIGNOR OF ONE-THIRD TO
CLARENCE J. MORLEY, OF DENVER, COLORADO, AND TWO-THIRDS TO
EDWIN F. ARTHUR, TRUSTEE.

PEN-PULLER.

No. 840,474

Specification of Letters Patent.

Patented Jan. 8, 1907.

Application filed October 23, 1905. Serial No. 283,941.

To all whom it may concern:

Be it known that I, FRANK CANFIELD, a citizen of the United States, residing in the city and county of Denver and State of Colorado, have invented certain new and useful Improvements in Pen-Pullers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in pen-pullers, my object being to provide a device of this class which shall be simple in construction, economical in cost, reliable, durable and efficient in use; and to these ends the 20 invention consists of the features, arrangements, and combinations hereinafter described and claimed, all of which will be fully understood by reference to the accompanying drawings, in which is illustrated an embodiment thereof.

In the drawings, Figure 1 is a top plan view of the paper-cutter provided with my improvement. Fig. 2 is a side view of the same. Fig. 3 is a view, shown on a larger 30 scale, illustrating the pen inserted prior to the pulling operation. Fig. 4 is a similar view showing the pen turned to the proper position for pulling. Fig. 5 shows the pen in the puller after it has been extracted from the holder.

35 The same reference characters indicate the same parts in all the views.

Let the numeral 5 designate a body part or handpiece or holder, which may consist of a 40 paper-cutter or not, as may be desired. This device 5 should be of sufficient length to allow it to be grasped by the hand during the pen-pulling operation. For convenience the device may be mounted upon one extremity 45 of a paper-cutter; but this is only for convenience, as the device may be separate or provided with any suitable construction enabling the user to hold the article firmly in the hand during the pulling operation. This 50 handheld part 5 is provided at one extremity with the pen-pulling device proper, consisting of a curved member 6, composed of two jaws 7 and 8, which, as shown in the drawings, are

formed integral with the body of the device. The stationary jaw 7 terminates at A, where 55 the metal is bent back upon itself, forming the movable or spring jaw 8, which coöperates with the stationary jaw 7 during the operation of pulling the pen. The jaw 8 is provided with an extension B, forming a 60 thumb-piece adapted to be pressed by the user during the pulling operation, whereby the pen is tightly gripped between the two jaws. The space between the jaws at the bend A is somewhat greater than at a short 65 distance from the bend to permit the easy insertion of the pen. Then by giving the pen a partial turn it is brought into the narrower space between the two jaws, when by the pressure of the thumb on the part B the pen 70 is tightly gripped and may be easily pulled from the holder. The jaws 7 and 8 are curved to conform approximately to the curve of the pen, whereby the latter may be caused to readily pass between the jaws or into the 75 proper position for pen-pulling purposes.

In the drawings the pen is designated by the reference character 10, and the holder by the character 12, both pen and holder being 80 of ordinary construction.

From the foregoing description the use and operation of my improved device will be readily understood. Assuming that the device is in the position shown in Figs. 1 and 2, the pen may be easily inserted by placing it in 85 such position that one of its edges enters the enlarged space between the jaws at the bend A. Then by giving the pen a partial turn or forward movement toward the body of the device the pen is brought into the lowest part 90 of the bend and also made to occupy the narrowest space between the jaws. The first position, or that of the pen when first inserted, is illustrated in Fig. 3, and the second position, or that after the pen has been adjusted to the 95 pen-pulling position, is illustrated in Fig. 4. When the pen is in the last-named position, the user of the device presses his thumb upon the extension B, causing the movable or spring jaw 8 to tightly grip the pen. The 100 pen-puller is then drawn away from the holder and the pen pulled out, when it occupies the position shown in Fig. 5.

Having thus described my invention, what I claim is—

1. A pen-puller comprising a handheld

part provided at one extremity with a curved pen-pulling member consisting of two jaws, one stationary and the other movable, the two jaws being curved longitudinally and occupying positions approximately parallel and having a space between them to receive the pen to be pulled when occupying a position at right angles to the length of the device, the movable jaw having sufficient yielding capacity to cause the pen to be tightly gripped when the movable jaw is pressed toward the stationary jaw.

2. A pen-puller comprising a gripping member composed of two jaws curved longitudinally to conform approximately to the curve of the pen and normally having sufficient space between them to permit the easy insertion of the pen at right angles to the length of the device, one of the jaws being yielding and provided with a thumb-piece extension for the purpose set forth.

3. A pen-puller provided with a pen-gripping device composed of two jaws bent longitudinally to conform approximately to the transverse curve of the pen when inserted in

a direction at right angles to the length of the device, one of the jaws being yielding and provided with a thumb-piece extension whereby the pen may be tightly gripped by pressing upon the yielding jaw for the purpose set forth.

4. A pen-puller consisting of a device composed of two members curved longitudinally to conform approximately to the transverse curve of the pen, one of the members being yielding and having a thumb-piece extension, the space between the members remote from the thumb-piece being sufficient to permit the easy insertion of the pen, in a direction at right angles to the length of the yielding member having sufficient yielding capacity to permit the gripping of the pen tightly by pressure upon the thumb-piece, substantially as described.

In testimony whereof I affix my signature in presence of two witnesses.

FRANK CANFIELD.
